Fig. 4.

Fig. 5.

Fig. 3.

FIG. 1 is a right side elevational view of an industrial trailer especially adapted for carrying golf carts and the like, showing my new design;

FIG. 2 is a top plan view thereof;

FIG. 3 is a front elevational view thereof;

FIG. 4 is a rear elevational view thereof;

FIG. 5 is a right side elevational view of an industrial trailer especially adapted for carrying golf carts and the like showing a second embodiment of my new design;

FIG. 6 is a top plan view thereof;

FIG. 7 is a front elevational view thereof; and

FIG. 8 is a rear elevational view thereof.

The left sides of the two embodiments, not shown in the drawings, are substantially the same as the respective sides shown therein.

The decking which is shown in only portions of the rectangular panels for ease of illustration, in FIGS. 2 and 6, covers the entire surface of said panels.

I claim:

The ornamental design for an industrial trailer especially adapted for carrying golf carts and the like, substantially as shown and described.
